UNITED STATES PATENT OFFICE.

OREN L. GRUBBS, OF INDEPENDENCE, KANSAS.

PHONOGRAPH-REPRODUCER.

1,315,117.

Specification of Letters Patent. Patented Sept. 2, 1919.

Application filed January 15, 1919. Serial No. 271,258.

To all whom it may concern:

Be it known that I, OREN L. GRUBBS, a citizen of the United States, residing at Independence, in the county of Montgomery 5 and State of Kansas, have invented a new and useful Phonograph-Reproducer, of which the following is a specification.

This invention relates to reproducers for phonographs, one of its objects being to 10 eliminate the scraping and other undesirable sounds ordinarily produced during the reproduction of sound.

A further object is to provide a reproducer utilizing a non-resilient member in 15 lieu of the ordinary flexible or resilient diaphragm and which member is movably supported by the stylus lever of the reproducer and which lever is resiliently mounted in a novel manner.

20 A further object is to provide simple and efficient means for preventing the escape of air past the yieldingly supported member.

With the foregoing and other objects in view, which will appear as the description 25 proceeds, the invention resides in the combination and arrangement of parts and in the details of construction hereinafter described and claimed, it being understood that within the scope of what is claimed, 30 changes in the precise embodiment of the invention shown can be made without departing from the spirit of the invention.

In the accompanying drawings the preferred form of the invention has been shown.

35 In said drawings:

Figure 1 is a central vertical section through a sound box having the present improvements.

Fig. 2 is a face view of the sound box, 40 all but a portion of the cap being removed.

Fig. 3 is a section on an enlarged scale taken on line 3—3, Fig. 2.

Referring to the figures by characters of reference 1 designates the body portion of 45 the sound box, provided with an interior shoulder 2 and which is also internally screw threaded as shown at 3. A cap 4 having a screw threaded peripheral portion 5 is adapted to engage the threaded portion 3 of the body 1 and to clamp on the marginal portion of a ring 6 formed of soft leather, balloon silk or other suitable flexible material secured to the margin of a disk 7 of wood or other non-resilient material. The 55 ring 6 extends very loosely from the disk 7 to the shoulder 2 on which it is clamped,

thus to allow the disk 7 to move back and forth relative to the body 1 and the cap 4 without interference from the ring.

The disk 7 is a floating disk, it being supported on the upper end of the stylus arm or lever 8 and which arm extends upwardly from a rocker 9 provided, at its ends oppositely disposed communicating frusto-conical openings. A socket member 11 having a 60 clamping screw 12 extends downwardly from the rocker 9 and in line with the arm 8 and is adapted to receive a needle N such as commonly used. The cap 4 is cut away to allow the rocker 9 to be attached to the 65 peripheral portion thereof and likewise to allow the arm 8 to extend between the cap 4 and the body 1. As shown in Figs. 1 and 3 of the cap 4 has an offset portion 13 which bridges over the arm 8.

70 Screws 14 extend through the opening 10 in the rocker 9 and mounted on each screw are oppositely disposed frusto conical plugs 15, formed of rubber and which are preferably hollow as shown at 16. 80 These plugs come together at their inner or small ends and are clamped tightly together and against the walls of the openings 10 by the screws 14, the large end of one plug of each pair bearing against the cap 85 4 while the large end of the opposed plug bears against the head of the screw 14. Thus it will be seen that the stylus arm or lever 8 is supported yieldingly and also serves to support the disk 7 yieldingly. Any 90 vibration produced by the movement of the needle 12 will be transmitted bodily to the disk 7 because of the yielding supporting plugs 15 on which the rocker 9 is mounted.

The back and forth movement of the disk 95 7 due to the vibration of the needle will result in the air in the space being vibrated so as to reproduce the sound recorded. The flexible ring 6 merely serves as a seal between the disk 7 and the wall of the body 1 so as to prevent leakage of air from the space 17 while it is being vibrated by the rapid reciprocation of the disk 7.

It has been found in practice that a reproducer such as herein described greatly 1 reduces the objectionable sounds, heretofore produced by the scraping contact of the needle with the record. It has also been found that the present reproducer gives a more natural tone than heretofore because 1 of the preservation of the overtones which are lost when the usual form of reproducer

is utilized. This reproducer eliminates the bending and crackling of the diaphragm and which has heretofore drowned out the pure overtures so desirable to reproduce.

5 What is claimed is:

1. A reproducer for phonographs including a sound box, a rocker arm having opposed openings therein, tapered plugs of elastic material seated in the openings, 10 screws extending through the plugs for attaching them and the rocker arm yieldingly to the sound box, a stylus lever extending from the rocker arm and into the sound box, and a movable disk fixedly mounted on said 15 lever.
2. A reproducer for phonographs including a sound box, a rocker arm having open-

ings extending through the ends thereof, each opening being flared outwardly at its ends, tapered plugs of elastic material seated within the flared ends of the openings, each plug being hollow, attaching screws extending through plugs and into the sound box for fastening the plugs and rocker arm to the sound box, a stylus lever extending from the rocker arm and into the sound box and a movable disk fixedly mounted on the arm. 20 25

In testimony that I claim the foregoing as my own, I have hereto affixed my signature in the presence of two witnesses.

OREN L. GRUBBS.
